UNITED STATES PATENT OFFICE

118,795

DESIGN FOR AN ELASTIC TEXTILE FABRIC

Charles E. Turk, New York, N. Y.

Application December 15, 1939, Serial No. 88,911

Term of patent 3½ years

To all whom it may concern:

Be it known that I, Charles E. Turk, a citizen of the United States of America, residing in the city of New York, county of New York and State of New York, have invented a new, original, and ornamental Design for an Elastic Textile Fabric, of which the following is a specification, reference being had to the accompanying drawing, forming part thereof.

The figure on the drawing is a plan view of an elastic textile fabric showing my new design.

The design unit is contained between the dot and dash lines which unit is repeated in regular succession as indicated by the extensions beyond the unit boundaries.

I claim:

The ornamental design for an elastic textile fabric, substantially as shown and described.

CHARLES E. TURK.
